UNITED STATES PATENT OFFICE.

GEORGE LITTLE, OF RUTHERFORD PARK, NEW JERSEY.

IMPROVEMENT IN RHEOSTATS OR RESISTANCE-COILS.

Specification forming part of Letters Patent No. 122,267, dated December 26, 1871.

To all whom it may concern:

Be it known that I, GEORGE LITTLE, of Rutherford Park, in the county of Bergen and State of New Jersey, have invented an Improvement in Rheostats or Resistance-Coils for Telegraph purposes; and the following is declared to be a correct description of the same.

This invention relates to a rheostat or resistance instrument that is adapted to telegraph operations, where the current is to be divided or its force regulated. This is effected by a sliding block and spring that connects the parts, so that more or less of a coil of insulated wire is brought into the electric circuit, thereby regulating the resistance to the current.

This instrument is shown in connection with a chemical telegraph for the purposes of illustration.

In the drawing, Figure 1 is a plan of the rheostat instrument, illustrating also the position thereof in the main line and the shunt to the chemical telegraph; and Fig. 2 is a vertical longitudinal section of said rheostat instrument.

The heads *a* and *b* are connected to each other by a tube of hard rubber, *e*, or other non-conducting material, and around this is wound tightly a coil, *e*, of insulated wire, the ends being in metallic connection with the heads *a* and *b*. The non-conducting covering of the wire *e* is caused to adhere in place or harden by heat or otherwise, and then the surface is dressed off to expose the wires without injuring the insulation. The main line wires *f* and *g* connect with the respective heads *a* *b*, so that the pulsations of

electricity would have to go through the entire coil *e*, if no other means were employed; thereby there would be a considerable resistance to the current. I however employ a movable conductor, *k*, that brings more or less of the coil *e* into action. The rod *l* is in metallic contact with the head *a*, but insulated in the head *b*; and upon this rod *l* is a sliding block, *m*, carrying the conductor *k*, the end of which rests upon the coil *e*, and the metallic contact is insured by a spring, *o*, in the block *m*, between the rod *l* and conductor *k*.

The rod *l* being insulated, the electricity cannot pass from the head *b* to the conductor *k*, except through the coil *e*, and according to the distance the conductor *k* is from the head *b* so the resistance will be more or less. The wires *p* *q*, passing from the heads *a* *b*, lead to the chemical telegraph apparatus and form the shunt or derived circuit, and the pen or stilus *r* and cylinder *s* for chemically-prepared paper illustrate this well-known character of telegraph apparatus.

I claim as my invention—

The conductor *k*, sliding block *m*, and spring *o*, in combination with the coil *e*, heads *a* *b*, and bar *l*, substantially as and for the purposes set forth.

Signed by me this 23d day of August, A. D. 1870.

GEORGE LITTLE.
